UNITED STATES PATENT OFFICE.

CHARLES F. POHLMAN AND HARRY THOMPSON, OF FREMONT, OHIO.

TOY CATAPULT.

SPECIFICATION forming part of Letters Patent No. 257,379, dated May 2, 1882.

Application filed August 6, 1881. (No model.)

To all whom it may concern:

Be it known that we, CHARLES F. POHLMAN and HARRY THOMPSON, of Fremont, in the county of Sandusky and State of Ohio, have 5 invented certain new and useful Improvements in Toy Catapults; and we do hereby declare that the following is a full, clear, and exact description of the invention, which will enable others skilled in the art to which it appertains 10 to make and use the same, reference being had to the accompanying drawings, which form a part of this specification, and in which—

Figure 1 is a perspective view of our improved toy catapult. Fig. 2 represents the handle 15 detached. Fig. 3 represents the elastic cord or band with the stone pouch or pocket detached from the handle, and Fig. 4 represents a modified construction of the handle.

Similar letters of reference indicate corresponding parts in all the figures.

Our invention relates to devices for slinging or shooting stones, marbles, and other missiles; and it consists in the detailed construction and combination of parts of a device or apparatus in the nature of a small portable catapult, 25 as hereinafter more fully described, and particularly pointed out in the claim.

The invention is designed as an improvement upon the patent granted to Jabez Smith 30 April 5, 1881, No. 239,865; and the essential feature of novelty consists in means for withdrawing the pouch without compressing its sides against the missile, and thus impeding the liberation of said missile.

In the annexed drawings, A is the handle, of 35 suitable size, into one end of which is inserted a forked or bifurcated rod or stout wire, B, held firmly in place by a ferrule, b, which also prevents the handle from splitting. Each of 40 the arms of the bifurcated rod B is bent to form a spring-hook, a a, at its outer end.

C is a strap, of india-rubber or other suitable elastic material; or a flexible coiled spring may be used, if desired. At each end of this

strap is a loop, eye, or small ring, c, which is 45 attached to the ends of rod B by its spring-hooks a; and to the middle of the strap is secured a small pouch or pocket, D, of leather or other suitable material, in which the missile is placed. To the back of this pocket is fastened 50 a small strap or loop, d, which serves as a handle in pulling the strap back in operating the device, as the pouch with the stone in it does not afford a ready means for holding.

In operating this apparatus the missile is 55 placed in the pouch, the handle A being held in the right hand while the pouch is being pulled back by its strap or tongue d with the left hand. By letting the tongue go suddenly the missile is shot out of its pouch with considerable force, and with a little practice the operator will soon acquire skill enough to hit small objects, such as birds or fruit, even when the birds are on the wing.

If desired, the construction of the parts A 60 B may be simplified by making the handle in one piece with the bifurcated rod B, as shown in Fig. 4.

Having thus described our improvement, we do not claim broadly the combination of the 65 forked handle and elastic band having the stone-pocket; but

What we claim, and desire to secure by Letters Patent of the United States, is—

In a toy sling or catapult of the described 70 construction, the elastic band C, having the pocket D, and strap or loop d, affixed to the back of said pocket, substantially as and for the purpose herein shown and specified.

In testimony that we claim the foregoing as 75 our own we have hereunto affixed our signatures in presence of two witnesses.

CHARLES F. POHLMAN.
HARRY THOMPSON.
